DOUBLE POINT IGNITION SET

Jesse T. Greene, Milledgeville, Ga., assignor of
one-half to Carl H. Massey, Milledgeville, Ga.

Application October 21, 1937, Serial No. 170,291

3 Claims. (Cl. 200—30)

This invention relates to breaker point assembly for internal combustion engine distributors and has for the primary object the provision of dual or double points and mountings therefor which will provide better engine performance with less consumption of fuel and will possess longer life.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a plan view, partly in section, and showing the dual or double points and mountings therefor, constructed in accordance with my invention.

Figure 2 is a sectional view taken on the line 2—2 of Figure 1.

Figure 3 is a fragmentary sectional view showing the dual contacts and the mountings therefor.

Figure 4 is a perspective view illustrating the contact arm.

Figure 5 is a perspective view illustrating the mounting for the pair of relatively fixed contacts.

Figure 6 is a perspective view illustrating the mounting for the pair of movable contacts.

Figure 7 is a perspective view illustrating a modified form of mounting for the relatively fixed contacts.

Referring in detail to the drawing, the numeral 1 indicates a fragmentary portion of an internal combustion engine distributor wherein the breaker arm cam is indicated by the character 2. Suitably secured in the distributor 1 is a mounting 3 including angularly related portions 4 and 5, the portion 5 being secured on the distributor 1 by stud bolts 6. The portion 4 has screw threaded openings to receive screw threaded contact carrying bolts 7, the contacts thereof being indicated by the character 8. The contacts 8 may be adjusted on the mounting 3 and are held in any of their adjusted positions by set bolts 9 threaded in openings 10 of the mounting 3 and turned against the contact carrying bolts 7.

A contact arm 11 is pivotally mounted on the distributor and carries a button 12 which rides the cam 2 under the influence of a spring 13, the latter also acting as an electrical conductor between the distributor housing and the contacts carried by the contact arm 11. Spaced ears 14 are formed on the contact arm 11 and receive a

pivot pin 15 which also extends through a contact mounting 16 on which are secured relatively spaced contacts 17 which cooperate with the contacts 8 in making and breaking the electric circuit of the distributor. A compound curved spring 18 bears against the mounting 16 and the contact arm 11. The spring will permit the mounting 16 to have a limited pivotal movement on the pivot pin 15 so that the contacts 17 adjust themselves to the contacts 8.

In lieu of the mounting 3 the contacts 8 may be secured on a substantially U-shaped mounting 19, the latter having slots 20 and an opening 21 for receiving stud bolts of a distributor housing whereby the mounting 19 may be easily adjusted. One end of the mounting 19 has an upstanding flange on which the contacts 8 are mounted. The mounting 19 being adjustable on the housing of the distributor permits the contacts 8 to be adjusted relative to the contacts 17.

The use of dual or double points has a distinct advantage over a single point in a distributor in that when the single point becomes burned a very weak current will be caused to pass through the points and consequently to the plugs, thereby causing inefficient operation of the engine, excessive gas consumption and, in some instances, will cause the engine to become inoperative. With the use of the double point the current is divided between the two pairs of points thereby decreasing the current through each pair of points which in turn reduces the possibility of burning of the points. In some instances small foreign substances may come between the points causing them to hold open and should this occur with the double point as heretofore described in this application the spring and pivot action will allow the double points to operate without interruption.

What is claimed is:

1. An interrupter for an ignition circuit, comprising a spaced parallel pair of like terminal contact members, an intermittently operable interrupter arm in cooperative relation to said terminal contact members, a rockable contact mounting on said arm, resilient means for yieldably holding said mounting in a neutral position, and a spaced pair of like contact members located on said mounting respectively at opposite sides of the pivotal axis thereof whereby to have a compensating engagement with said first mentioned terminal contact members.
2. An interrupter for an ignition circuit, comprising a spaced parallel pair of like terminal contact members, means for individually adjust-

ing said contact members longitudinally, an intermittently operable interrupter arm in cooperative relation to said contact members, a rockable mounting pivotally attached intermediate its ends to said interrupter arm, a compound curved spring element interposed between said mounting and said interrupter arm for holding the mounting in a normally neutral position, and a spaced pair of contact members located on said mounting respectively on opposite sides of the pivotal axis thereof whereby to have a compensating engagement with said first mentioned terminal contact members.

3. In an interrupter device of the character described, a supporting body, a dual point circuit terminal comprising a spaced pair of contact members of like character and capacity, an in-

termittently operable interrupter arm pivotally mounted and normally yieldably urged towards said terminal contact members, and a dual point opposed circuit terminal carried by said interrupter arm and comprising a rockable mounting having an off-set pivotal attachment intermediate its ends to said interrupter arm with interposed compound curved spring element yieldably holding the mounting in a normally neutral position, and a pair of contact members of like character and capacity as first mentioned terminal contact members and located on said rockable mounting respectively on opposite sides of the pivotal axis thereof whereby to engage said first mentioned terminal contact members with equalizing effect. 5 10 15
